8 Claims. (Cl. 94—45)

This invention relates to apparatus for the surfacing of plastic bodies and particularly to apparatus intended to be used for finishing surfaces of concrete slabs such as floor slabs. This invention is a modification on the apparatus disclosed and described in detail in our application Serial No. 682,716 filed September 9, 1957.

Priorly, various types of mechanically operated mechanisms have been developed which were designed and intended to reduce to the minimum the amount of manual labor which must be expended and the time required to reduce to a true plane and impart the desired surface finish to plastic bodies such as concrete floors, walks and roadways. A number of these mechanisms have come into widespread use, some particularly designed for use on roadways and others primarily intended for employment in the surfacing of floors. A known type of mechanically operated surface mechanism comprises a work engaging member, a motor coupled to the work engaging member for rotating the work engaging member and a handle which prevents rotation of the motor casing and constitutes a means for moving the implement over the surface of a concrete body in the desired manner.

One particular form of mechanism known in the art includes a mechanism for imparting to the rotating work-engaging member high frequency vibrations so that the plastic body below the apparatus is not only subjected to the action of the rotating disc but is subjected to high frequency vibrations. Such apparatus is highly effective and enables the user to properly surface a plastic body, such as a concrete floor, in a vastly improved manner. Thus, by the aid of the rotating and vibrating disc, an extremely dry concrete mixture may be surfaced, a mixture having a low water-cement ratio that it cannot be surfaced by ordinary means or methods since it is impossible to laterally displace or horizontally push material from the higher areas of the concrete onto the lower areas. The leveling of the floor surface is brought about by vertically depressing the higher areas instead of laterally displacing these areas and the concrete slab or the like which is produced is of superior construction, being more dense and free of voids. The surface is superior inasmuch as this method of leveling the same results in bringing to the surface a relatively stiff paste of cement and fine sand barely sufficient in thickness for the fine trowelling by hand. The improved method not only gives a superior product but insures substantial surfacing in time and labor costs. However, we have discovered that in employing vibratory and rotary motion to finish the concrete, it is not always necessary to employ both vibratory and rotary motion. For example, after the higher areas are vertically depressed and the plastic body approaches a level surface then the vibratory motion may be discontinued while maintaining the rotary motion to thus achieve an extremely smooth surface. One example of rotary and vibratory surface finishing machine is disclosed and described in detail in R. E. Davis Patent No. 2,386,843, issued October 16, 1945.

Briefly, in accordance with the invention disclosed in our above mentioned application, a concrete finishing machine is enclosed in a stationary housing and provided with a cam plate associated with a wear or floor

2

finishing plate. A group of spring biased plungers are mounted on the housing and are operatively linked to the cam surfaces by means of rollers mounted on the plungers. The prime mover or source of power for the machine is coupled to the wear plate by means of a splined shaft and a splined plate to impart rotary motion while permitting axial vibratory motion of the wear plate. The shaft is spring biased by a helical shock absorber spring secured between the cam or master plate and the end of the shaft. The plungers are moved upwardly by the movement of the rollers upon the cam surfaces and the motion of the plungers may be selectively discontinued by means of hydraulic cylinders and pistons located in the cylinders and each coupled to a plunger. As the cam plate is rotated by means of the splined shaft, the rollers ride the cam surfaces and the connected plungers move out of engagement with the cam plate and return to the cam plate under the influence of the impact springs. Thus, the energy imparted to the impact springs by the cam plate is imparted to the plungers to return the plungers to the cam plate, thereby giving a vibratory motion to the connected wear plate.

In accordance with other aspects of the invention disclosed in our above mentioned application, the plungers may be moved away from the cam or undulation plate by the operator during the finishing operation such that the rollers are disengaged from the cam surfaces. The reciprocating motion of the plungers formerly caused by the cam plate is thus terminated. The operator may thus terminate the vibratory motion imparted to the wear plate and hence to the concrete floor without modifying the rotary operation.

In accordance with other aspects of the invention disclosed in our above mentioned application, the plungers are spaced approximately 90° apart on the housing of the machine while opposite pairs of the plungers are offset a few degrees so that a beat frequency is generated by the cooperation of the plungers and the cam plate. By means of this beat frequency, the number of vibrations imparted to the wear plate and hence to the floor is greatly increased without the requirement that the wear plate be rotated at exceedingly high speeds.

During subsequent tests we have determined that still further improved results may be achieved by increasing the vibrating frequency and impact of the reciprocating plungers while actually decreasing the power required to be imparted to the plungers. We have also discovered a novel pump mechanism for selectively controlling the actuation of the reciprocating plungers.

Accordingly, it is an object of this invention to provide an improved concrete finishing machine.

It is another object of this invention to provide an improved concrete finishing machine which is adapted selectively to apply vibratory motion to the concrete mass.

It is another object of this invention to provide an improved vibratory-rotary concrete finishing machine which is simple in construction and operation.

It is another object of this invention to provide an improved concrete finishing machine in which vibratory motion of a higher frequency is imparted to the concrete mass from a single prime mover and the vibratory impact is increased without increasing the speed of the prime mover and while decreasing the power required to be imparted to the reciprocating plungers.

It is another object of this invention to provide an improved vibratory and rotary concrete finishing machine which is simple in construction and operation and thus economical to build.

It is another object of this invention to provide an improved fluid system for selectively controlling the actuation of the reciprocating plungers.

It is another object of this invention to provide an im-

proved fluid pump for the fluid system which controls the actuation of the reciprocating plungers.

It is another object of this invention to provide the fluid system pump with a piston which, in addition to pumping fluid, also may be employed to operate selectively a valve associated with the pump.

It is a further object of this invention to provide the fluid control system of the machine with a piston which provides an additional fluid passageway for the fluid when the piston moves to open the valve associated with the pump.

It is a further object of this invention to provide the fluid control system of the machine with a pump having a piston which may be employed to release the pressure in the fluid system by opening a fluid valve associated with the pump and simultaneously providing a passageway through the piston to the fluid reservoir.

Briefly, in accordance with aspects of this invention the reciprocating plungers are reciprocatingly mounted with respect to the fluid actuating pistons so that they may reciprocate independently of the piston. Thus the pistons, which introduced a frictional drag on the walls of the cylinder and reduced the effective impact of our prior machine, do not move with the reciprocating plunger but are nevertheless actuatable to raise the plungers so that the rollers will be disengaged from the cam surfaces on the wear plate. Such movement is possible since the piston has a hollow tubular extension having an annular flange on the inner periphery which engages an annular protrusion or shoulder on the reciprocating plunger. A plurality of curved members, such as metallic buttons, are mounted in the wear plate between the cam surfaces and are engaged by the tip of the reciprocating plunger. Advantageously, these buttons are located concentrically with respect to the cam surfaces and are positioned to engage the tip of the plunger immediately after the associated roller has passed over the crest of the cam surfaces. The buttons thus cause the reciprocating plunger to have a vibratory motion at a frequency greater than that produced by the rollers and cam surfaces alone. Further, since the plunger is reciprocally mounted with respect to the fluid piston, the piston does not act as a damping device to reduce the impact of the plungers.

It is another feature of this invention to provide undulatory surfaces on the wear plate intermediate the cam surfaces to engage the reciprocating plungers and thus impart a greater frequency of vibration than could be achieved by the cam surfaces alone.

It is another feature of this invention to provide undulatory surfaces on the wear plate concentrically arranged with respect to the cam surfaces, which undulatory surfaces engage the tip of the reciprocating plungers and thus increase the frequency of the reciprocation of the plungers without increasing the speed of motion of the wear plate.

A complete understanding of this invention and of these and various other features thereof may be gained from a consideration of the following detailed description when read with the accompanying drawing in which:

FIGURE 1 is a view in elevation, partly in section, of a portion of a cement finishing machine in accordance with one illustrative embodiment of this invention;

FIGURE 2 is a view of the extreme left hand portion of FIGURE 1 to a larger scale.

FIGURE 3 is a plan view, partly in section, taken on line 3-3, of FIGURE 1.

FIGURE 4 is a view taken along the lines 4-4 of FIGURES 2 and 3.

FIGURE 5 is a view in elevation, partly in section, of the fluid pump and a portion of the handle.

Referring now to the drawing, there is depicted one illustrative embodiment of this invention. As shown in FIGURE 1, a concrete finishing machine housing 10 has a suitable prime mover 12 mounted thereon. This prime mover may be of any convenient type such as an internal

combustion engine or an electric motor. A shaft 14 is connected to prime mover 12 and has a pulley 16 secured thereto to provide a means for operatively connecting the prime mover with the concrete contacting plate as will be subsequently explained. A shaft 20 is rotatably mounted in housing 22 and has a pulley 18 secured thereto. Pulleys 16 and 18 are connected by means of a suitable V belt (not shown). A worm gear 21 is mounted on and secured to shaft 20 within housing 22. A wheel gear 23 is secured to vertical shaft 24 and positioned adjacent worm gear 21 so that worm gear 21 drives wheel gear 23 when shaft 20 is rotatably mounted by the prime mover 12. Shaft 24 is rotatably mounted in housing 10. Drive plate 26 is secured to the lower end of shaft 24 by means of nut 66.

Spaced around the periphery of drive plate 26 are a plurality of bolts 28 used to interconnect drive plate 26 and master plate 32. Resilient bushings 30 surround each of bolts 28 and are held in place by plates 29 which are secured to plate 26 by bolts 31. Bushings 30 provide means for coupling the plate 26 to master plate 32 while preventing the vibration of master plate 32 from being transmitted to the gears 21 and 23, prime mover 12 and to the operator of the machine. Vibration of gears and the prime mover would cause excessive wear. Additionally, this vibration, if allowed to reach the handle, would make the machine difficult for the operator to control.

Wear plate 34, which contacts the surface to be finished, is connected to master plate 32 by means of suitable bolts 36. A plurality of plunger assemblies 38 are mounted around the periphery of housing 10. Any convenient number of plunger assemblies may be employed, depending on the frequency of vibration desired. For example, six may be employed and they may be spaced approximately 60° apart. If it is desired to develop a beat frequency, the spacing between certain of the plunger assemblies may be different from the spacing between certain other plunger assemblies. The development of a beat frequency by plunger spacing is disclosed and described in our application Serial No. 682,716 filed September 9, 1957. The plungers 40, reciprocably mounted in these assemblies, are employed selectively to impart vibratory motion to wear plate 34 in response to the rotation of wear plate 34 by the prime mover, as will be subsequently explained.

As best seen in FIGURE 2, rollers 42 are rotatably mounted on the lower portion of plungers 40 and these rollers operatively engage cam surfaces 43 and 45. A plurality of undulatory impact buttons 44 are concentrically arranged with respect to cam surfaces 43 and 45 in plate member 32. These impact buttons engage the tips 47 of plungers 40 to produce supplemental vibrations as will be subsequently explained.

Pistons 48 are slidably mounted in the upper housing of each of plunger assemblies 38. These pistons include a tubular extension 52 having an axial passageway therethrough to permit the plungers 40 reciprocated relative to the pistons and to act as a guide member for the reciprocating plungers 40. A suitable fluid seal 50 is secured to the lower portion of the outer periphery of piston 48. Tubular extension 52 also acts as a guide member for the reciprocating plungers 40. These tubular extensions 52 have an annular shoulder 53 on their inner surface. Shoulder 52 engages annular ring 55 on the plungers 40 when the pistons 48 are moved upwardly by the introduction of fluid between pistons 48 and the housings of plunger assemblies 38. This fluid is pumped through fluid passage 56 from a pump conveniently located on the machine handle, which will be subsequently described. The upward movement of pistons 48 disengages the reciprocating plungers from the impact buttons 44 and disengages the rollers 42 from the cam surfaces 43 and 45. Shoulders 53 are located at a point sufficiently removed from the upper surfaces of pistons

48 to permit the plungers to reciprocate freely when the piston is in its lower position, as shown in FIG. 2. Fluid sealing washers 57 and 58 are positioned in the housings of the plunger assemblies 38 to provide a fluid seal between the housings and the tubular extensions 52.

Helical springs 62 surround a portion of each plunger 40 and engage annular shoulders 63 of each plunger 40 and the lower surface of cylindrical member 64 which defines the upper portion of housing 10 in the regions of the plungers 40. The plunger assemblies 38 are secured to housing 10 by means of suitable bolts 65. The tops of plunger assemblies 38 are defined by members 67 which are secured by suitable bolts 68.

In order to prevent the entry of foreign particles into the machine housing, a shield 70 is secured to the master plate 32 by means of suitable bolts 72. This shield is cylindrical in shape and extends from the master plate 32 to a region adjacent the lower surface of housing 10, thus preventing the entry of foreign matter between housing 10 and wear plate 32.

The operation of the reciprocating plungers might be explained with regard to FIG. 4 which shows the relationship of cam surfaces 43 and 45 and impact buttons 44. As shown in FIGURE 4, rollers 42 co-operate with cam surface 45 to produce reciprocating motion of the piston 40. Cam surface 45 includes a substantially flat trough 100 and a peak or crest 102 at the termination of an incline plane 104, which plane is connected to a trough 100. The entire length of a given cam surface is measured from one crest or peak to the next crest or peak and this length is termed "the cam pitch." The extreme lower portion 106 of plunger 40 is disengaged from the undulatory buttons 44 when the rollers 42 ride up on the incline planes 104 as master plate 32 is rotated by the prime mover. When rollers 42 pass their respective crests 102, the energy stored in spring 62 is imparted to the plunger or piston 40, causing plunger tip 106 to strike the undulatory button 44 as shown in the middle dotted line of FIGURE 4 and thus impart vibratory motion to the master plate 32 each time the rollers 42 pass a pair of crests 102.

Since the plungers 40 are not rigidly connected to pistons 48, these pistons do not move with the plungers. Thus, the plungers do not incur frictional losses which might be introduced by the pistons sliding up and down the cylindrical chambers, as they would if the pistons were secured to the plungers. Thus by virtue of the reduced drag, less power is required to drive the reciprocating plungers than would be required if the pistons were secured to the plungers. Further, even though less power is required an increase impact force is obtained since the pistons do not slow the downward motion of the plungers. Advantageously, a higher rate or frequency of impact is achieved by the use of the impact buttons 44 which engage the tips 47 of plungers 40 and this increased frequency of impact is achieved with less driving power than the devices of the type disclosed in our application Serial No. 682,716 filed September 9, 1957.

Referring now to FIG. 5 there is depicted a portion of handle 80 having a fluid pump 82 mounted thereon. This fluid pump 82 is connected through a suitable flexible conduit or hose 84 to pipe 56 located within housing 10. Pump assembly 82 includes a fluid reservoir 85, a piston housing 87, a pair of piston members 89 and 91, a ball check valve 93, biased into a closed position by spring 95, and a pump handle assembly 97. Fluid reservoir 85 is provided with a ball type vacuum relief valve 99 and a cover 101 which threadably engages the reservoir 85 to permit fluid to be inserted in the reservoir. Piston member 89 is provided with a fluid seal 103 located in an annular recess 105 to prevent the passage of fluid between the piston member 89 and the piston housing 87.

Advantageously, piston member 91 is provided with a threaded portion 107 which threadably engages the inner wall of piston member 89 so that rotation of member 91

by means of knurled nut 109, produces axial movement of piston member 91 with respect to piston member 89. A radial passageway 111 is provided through piston member 89 and this passageway communicates with an aperture 113 in reservoir 85 when piston member 89 is at the forward end of its stroke.

Advantageously, piston member 91 has a reduced portion 115 which provides a passageway between member 91 and the inner wall of piston member 89. This passageway is connected with passageway 111 and also connects with hose or conduit 84 when member 89 is advanced by rotation of knob 109 to unseat ball check valve 93. The normal position of member 91 is that shown in FIG. 5 in which enlarged member 117 acts as a valve to seal the passageway between piston members 89 and 91 so that the two piston members may act as a single unit to pump fluid from reservoir 82 into hose 84.

The operation of the fluid pump is as follows: When the handle assembly 97 is manually moved to the opposite end of its stroke, as shown in the dotted outline, piston members 89 and 91 are withdrawn beyond aperture 113 and fluid passes from reservoir 85 into the chamber thus provided between the ends of piston members 89 and 91 and ball check valve 93. When the handle assembly 97 is returned to the end of its stroke, as shown in solid lines, the fluid in the chamber is subjected to pressure and the fluid causes the valve 93 to be unseated. When valve 93 is unseated, the fluid passes around the valve into conduit 84. When the piston reaches the end of its stroke, the ball check valve is again forced into its seated position by spring 95 and the cycle may be repeated until sufficient fluid pressure is built up within chambers 41 to cause the pistons 48 to move into their uppermost position. Pistons 48 thus lift plunger tips 47 out of engagement with impact buttons 44 and rollers 42 out of engagement with cam surfaces 43 and 45. Thus the reciprocation and resulting impact of the plungers may be selectively discontinued. When the operation of the reciprocating plungers is discontinued, the wear plate 34 may be rotated and used as a vibrationless means for achieving a fine finish on the concrete surface. This step is usually employed after the concrete has reached a relatively smooth surface and it is merely necessary to achieve a polishing action on the upper surface of the concrete without laterally displacing portions of the concrete. With such an arrangement, it is possible for the operator to employ both rotary and reciprocating motion to displace the concrete from the "peaks" into the "valleys" during the initial stages of finishing the concrete surface and employing only rotary motion to achieve a high degree of finish after a relatively smooth surface has been achieved. If the operator then desires to move into a new or unfinished portion of the concrete surface and again employ vibratory rotation, he merely rotates handle 109 until member 91 moves to unseat ball check valve 93. Simultaneously with the displacement of ball check valve 93 from its seat, a passageway is provided between piston members 89 and 91, through apertures 111 and 113 to the fluid reservoir 85. Helical springs 62 now act to restore plungers 40 to their lower position and thus aid the fluid under pressure to cause the fluid in chamber 41 to be driven through conduits 46 and 84 back to reservoir 85. When the fluid pressure is equalized by the return of a substantial volume of fluid to the reservoir, then handle 109 may be rotated to reseat member 113 in piston member 89 and to permit ball check valve 93 to return to its seat. Under these conditions, the plunger rollers 42 and plungers 40 impart vibratory motion to the surface of the concrete by wear plate 34 and the cycle of operations may be repeated.

Thus, it is apparent that this simple concrete finishing machine achieves a high rate of vibratory motion to finish the surface of the concrete and this high rate of vibration is achieved with less power than in machines of the type known in the art.

It is also apparent that the fluid system of this machine includes a simple pump to control selectively the actuation of the reciprocating plungers by means of an unusual piston assembly, a portion of which piston assembly acts simultaneously to open a ball check valve and to open a passageway through the piston which communicates with the fluid reservoir.

While the principles of this invention have been explained with reference to one illustrative example, it is understood that they may be applied to various other equivalent embodiments without departing from the spirit and scope of this invention.

We claim:

1. In a concrete finishing machine or the like, a stationary housing, a wear plate rotatably mounted relative to said housing, means for rotating said wear plate, cam surface means on said wear plate, impact surfaces intermediate said cam surface means, reciprocating plunger means mounted in said housing at intervals around said housing above said cam surface means for selectively engaging said cam surfaces and said impact surfaces, fluid actuating means for selectively delivering a fluid, and fluid actuated means coupled to said fluid actuating means and slidably coupled to said reciprocating plunger means and having cooperating shoulders thereon, each fluid actuated means having an internal shoulder cooperating with an external shoulder on one of said plunger means for selectively lifting said plunger means out of engagement with said cam surfaces and said impact surfaces in response to the delivery of fluid from said fluid actuating means to said fluid actuated means.

2. In a concrete finishing machine or the like, according to claim 1 wherein said impact surfaces include a plurality of impact buttons defining curved surfaces which are struck by the tips of the said plunger means to produce vibratory motion of said wear plate.

3. In a concrete finishing machine or the like, in accordance with claim 1 wherein said fluid actuating means includes a piston housing, a piston reciprocably mounted in said housing, a valve defining a closure of one end of said housing and a fluid reservoir having an aperture therein defining a fluid passage to said piston housing, said fluid actuating means including means for moving a portion of said piston relative to another portion of said piston to provide a fluid passage between said valve and said aperture, and means for reciprocating said piston within said housing.

4. In a concrete finishing machine a combination comprising a housing, a concrete contacting wear plate rotatably mounted relative to said housing and having cam surface means connected thereto, a plurality of vibratory plungers reciprocably mounted in said housing at intervals around said housing above said cam surface means to engage said cam surface means at one end of their stroke to produce vibratory motion, said plungers having rollers thereon, said cam surface means being positioned to engage said rollers, spring means on said plungers for moving said plungers toward said wear plate, piston means slidably connected to each of said plungers, each of said piston means having an internal shoulder thereon cooperating with an external shoulder on one of said

plungers for lifting said plunger when said piston means is moved away from said wear plate and fluid means for moving said piston means in a direction to disengage said rollers from said cam surfaces while said wear plate continues to rotate, selectively to terminate the vibratory motion produced by said plurality of plungers.

5. In a concrete finishing machine the combination according to claim 4 wherein said fluid means comprises a fluid reservoir, a piston housing secured to said reservoir and having a passage communicating therewith, a pump piston reciprocably mounted therein, a valve positioned in a valve seat in said housing, spring means urging said valve against said valve seat, said pump piston being movable to a position to unseat said valve from said valve seat.

6. In a concrete finishing machine according to claim 5 wherein said pump piston comprises an outer cylindrical member having a radial passage therethrough which communicates with said reservoir only when said pump piston is at the end of its forward stroke and an inner rod portion, one end of which has an outer diameter substantially equal to the inner diameter of said outer cylindrical member, the other end of which inner rod portion has a diameter of said outer cylindrical member to provide a passage therebetween, which rod portion terminates in an enlarged portion which seats against a recess in the end of said outer cylindrical member to act as a valve to close the fluid passage through said piston.

7. In a concrete finishing machine according to claim 6 the combination further comprising first handle means for advancing said inner rod member with respect to said outer cylindrical member to unseat said enlarged terminal portion of said rod member thereby opening the fluid passage through said piston and contacting said spring urged valve to open said valve and permit the passage of fluid around said valve, through said piston to said reservoir.

8. The combination according to claim 4 wherein said shoulder is on the inner surface of said piston means and wherein one of said vibratory plungers is reciprocably mounted within each of said piston means and has a shoulder thereon positioned to engage the shoulder on said piston means, said fluid means including means for moving said piston means whereby said shoulders engage and move said vibratory plunger away from said wear plate, thereby disengaging said rollers from said cam surface.
